PORTABLE REFRIGERATOR

Walter F. Ohme and Emil E. Farms, Minneapolis, Minn.

Application May 22, 1933, Serial No. 672,188

4 Claims. (Cl. 220—9)

Our invention relates to refrigerators and particularly to portable refrigerators.

An object of the invention resides in providing a portable refrigerator which is extremely inexpensive in construction and light in weight.

Another object of the invention resides in providing a portable refrigerator which is neat and attractive in appearance and which is sturdy and substantial in construction.

10 A still further object of the invention resides in constructing the refrigerator with a box-like skeleton frame including angle corner members at the corners and in employing sheets of insulating material held in place against said corner members and exposed upon the exterior through the space between the corner members.

Another object of the invention resides in constructing the upper edges of the walls of the box-like frame with flanges bent inwardly therefrom and overlying the upper edges of said sheets of insulating material for holding said sheets from endwise movement.

20 A feature of the invention resides in employing a container fitting closely within the sheets of insulating material and serving to hold the sheets against the walls of the frame and in engagement with said flanges.

Another object of the invention resides in providing the container with flanges overlying the 30 ends of the sheets of insulating material, said last named flanges extending toward and being spaced from the first named flanges to form a heat transmission seal between the interior and exterior of the refrigerator.

35 An object of the invention resides in constructing the outer box-like structure of the refrigerator from sheet metal and in further constructing the bottom with flanges extending upwardly therefrom and joined at the corners.

40 A still further object of the invention resides in attaching the angle corner members to the flanges of the bottom at the corners so as to stiffen and reinforce the outer structure at the corners.

Another object of the invention resides in connecting the upper ends of the corner members with a band and in constructing the said band with the flange for engagement with the upper end of the insulating sheets.

45 An object of the invention resides in constructing the refrigerator with a cover overlying the upper ends of the walls of the body thereof and having a lip depending therefrom and encircling the box-like structure and in further constructing said cover with an insulating sheet attached to the cover and extending downwardly into the container.

50 Another object of the invention resides in constructing the refrigerator with a U-shaped handle having two legs and a connecting portion, said

legs being provided with inwardly facing trunnions pivoted to the box-like structure of the refrigerator, said handle being adapted to swing over the cover of the refrigerator when in raised position. An object of the invention resides in 5 providing a strut on the upper part of the cover adapted to extend upwardly toward the connecting part of the handle and in further providing the strut with latching means for engagement with the handle to hold the handle in proper 10 position.

A feature of the invention resides in constructing the handle of somewhat resilient material and in further constructing the connecting portion as a bar adapted to yield upon the application 15 of pressure thereto.

An object of the invention resides in constructing the strut with a groove and with two cam members having cam surfaces spiralling with respect to the axis of said trunnions for leading the 20 connecting portion of the handle into said groove.

Other objects of the invention reside in the novel combination and arrangement of parts and in the details of construction hereinafter illustrated and/or described. 25

In the drawing:

Fig. 1 is a perspective view of a portable refrigerator illustrating an embodiment of our invention.

Fig. 2 is an elevational cross sectional view 30 taken on line 2—2 of Fig. 1.

Fig. 3 is an elevational longitudinal sectional view taken on line 3—3 of Fig. 2.

Fig. 4 is a plan sectional view taken on line 35 4—4 of Fig. 3.

Fig. 5 is a fragmentary vertical sectional view taken through the cover and the upper part of one of the walls of the body of the refrigerator.

In the construction of portable refrigerators, it 40 is a highly desirable requisite that the refrigerator be strong and sturdy in construction and still be light in weight and attractive in appearance. The present invention provides a device which fully meets all of these requirements.

The invention comprises an outer box-like structure or frame which we have indicated in its entirety at A and an inner container B spaced and insulated therefrom. Both the outer box-like structure and the container are open at the 50 top to give access to the interior of the refrigerator and are adapted to be closed through a cover C. These parts will now be described in detail.

The outer box-like structure A is in the nature of a skeleton frame and is constructed entirely 55 from sheet metal. This frame includes a bottom 10 which is formed with flanges 11, 12, 13 and 14 bent upwardly from the edges thereof and joined at the corners. At the corners of the box-like structure are provided angle corner mem- 60

bers 15, 16, 17 and 18 which are constructed with legs 19 and 20 extending angularly outwardly from one another at right angles. These angle corner members overlie the outer surfaces of the flanges 11, 12, 13 and 14 and are attached thereto as by riveting or spot welding. At the upper ends of the corner members is provided a band 21 which may be constructed of a single strip of material bent to form parts 26, 27, 28 and 29 which conform to the dimensions of the frame and are fitted within the reentrant angles of the corner members 15, 16, 17 and 18. This band is joined at one of the corners and is welded to all of said corner members in the same manner as the flanges of the bottom of the box-like structure. If desired, the band 21 may be made in several pieces and the joints between the pieces arranged in the corners the same as the joint between the ends of the structure shown.

Within the interior of the refrigerator are placed a number of sheets of insulating material designated at 22, 23, 24 and 25. These sheets fit up against the flanges 19 and 20 of the various corner members of the box-like structure as well as against the flanges 11, 12, 13 and 14 and the parts 26, 27, 28 and 29 of band 21. For the purpose of holding the said sheets of insulating material from movement within the interior of the box-like structure, the upper edges of the parts 26, 27, 28 and 29 of the band 21 are formed with inwardly extending flanges 30 best shown in Figs. 2, 3 and 5. These flanges overlie the upper edges of the sheets of insulating material 22, 23, 24 and 25 which are snugly received between the same and the bottom proper 10 of the outer structure of the refrigerator.

The sheets of insulating material 22, 23, 24 and 25 are held against the various parts of the box-like structure through the action of the container B which is inserted endwise through the open end of the refrigerator. This container is preferably constructed of sheet metal, being provided with side walls 31 and 32 and end walls 33 and 34. The said side and end walls have attached to them at their lower ends a bottom 35 which is secured to said walls through a seamed joint 36. These walls all fit snugly against the inner surfaces of the sheets of insulating material 22, 23, 24 and 25 and hold the same in contact with the outer walls of the box-like structure. Between the bottom 35 of the container B and the bottom 10 of the box-like structure A is disposed another sheet of material 37 which is of a thickness such as to hold the seams 36 away from the bottom 10 and to provide insulation between the interior of the container B and the exterior of the refrigerator.

At the upper ends of the walls 31, 32, 33 and 34 are formed inwardly turned flanges 38 which engage the upper edges of the sheets of insulating material 22, 23, 24 and 25 in much the same manner as the flanges 30 and said flanges are of such lateral extent that the same fall short of the flanges 30 and provide a space therebetween extending perimetricaly about the entire upper edge of the refrigerator. By means of this construction a heat transmission seal is formed between the interior of the refrigerator, thereby preventing rapid transmission of heat through the wall structure of the refrigerator by conduction directly through the metal parts.

The open end of the refrigerator is closed through cover C which is best shown in Figs. 2 and 3. This cover is constructed from sheet metal in much the same manner as the bottom

10 and comprises a top 39 which has bent downwardly from the edges thereof lips 40 adapted to overlie the outer surfaces of the band 21. Upon the interior of the cover C is provided a sheet of insulating material 41 which is of such dimensions as to fit within the interior of the container B. This sheet of insulating material is covered by a liner 42 which has flanges 43 bent upwardly therefrom and extending toward the top 39. These flanges fall short of the said top 10 to provide another heat transmission seal by means of which transmission of heat from the cover to the member 42 is prevented. The liner 42 and insulating sheet 41 are attached to the cover C in a manner to be presently described 15 in detail. As will be noted in Figs. 2 and 3 the flanges 43 are spaced from the lips 40 to leave a channel 44 extending perimetricaly about the cover. The upper edge of the wall structure of the refrigerator is received within this channel. A strip of felt 45 or similar cushioning and heat insulating material is disposed within this channel which is adapted to engage the upper edge of the wall structure of the refrigerator and to contact with the flanges 30 and 38. This strip 25 forms a seal for the refrigerator by means of which the transmission of heat to the interior of the refrigerator by convection is entirely prevented.

For the purpose of handling the refrigerator, 30 a handle is employed which is indicated in its entirety at D. This handle is constructed of heavy wire or rod which is bent U-shaped in form to provide two legs 46 and 47 and a connecting portion 48. The connecting portion 48 is preferably in the form of a straight bar or rod extending completely across the refrigerator and parallel with the top 39 of cover C. The lower ends of the legs 46 and 47 are provided with trunnions 49 and 50 which extend toward one another and lie in axial alignment. These trunnions are journaled in plates 51 and 52 which are attached to the parts 27 and 28 of the band 21 through welding, riveting or otherwise. The legs 46 and 47 are spaced apart a distance such 45 that the same straddle the cover C. By means of the plates 51 and 52 the weight of the refrigerator may be transferred to the handle 48 through the frame structure without unduly stressing any of the parts of the refrigerator. The handle 48 50 may be arranged in the position shown in Fig. 1 in which the refrigerator may be readily handled and manipulated or the same may be swung downwardly toward one side of the refrigerator in which position the cover C may be removed 55 from the refrigerator and access to the interior thereof procured.

For the purpose of securing the cover C in position upon the open end of the refrigerator, the handle D is utilized. Operating in conjunction therewith is a strut 53 which is preferably constructed of bar metal which is bent in the shape shown. This strut is formed with two legs 54 and 55 having ears 56 and 57 extending outwardly from the lower ends thereof. Rivets 58 65 and 59 extend through the ears 56 and 57, the top 39, and also through the insulating sheet 41 and the liner 42. Sleeves 66 disposed between the top 39 and liner 42, through which the rivets extend hold the said parts in proper spaced relation. These rivets serve the dual purpose of holding the strut 53 attached to the cover A as well as holding the insulating sheet 41 and the liner therefor attached to the interior of the cover. The two legs 54 and 55 are provided with 75

a connecting portion 60. This portion is constructed at the center with a groove 61 and adjacent the said groove with two parts 62 and 63 formed with cam surfaces spiralling with respect 5 to the axis of the two trunnions 49 and 50. The handle D is preferably constructed of a somewhat resilient material and the two cam surfaces of parts 62 and 63 serve to spring the bar 48 of the said handle out of alignment and to 10 direct the same into the groove 61. When the said handle becomes so disposed as indicated in Figs. 1 and 2, the cover C is forced down against the upper part of the body of the refrigerator and held in proper position. When so disposed 15 the parts are firmly latched and the refrigerator may be easily connected about.

The use of our invention is as follows: When the refrigerator is desired for use the bar 48 of handle D is forced over either of the two parts 20 62 and 63 of the strut 53, which permit the handle being swung downwardly to a position overlying the cover C. Cover C may then be raised and withdrawn from the refrigerator proper. The commodities to be cooled are then 25 placed within the refrigerator which has a suitable refrigerating substance such as ice or solidified carbon dioxide may also be introduced. The cover is then again applied and the bar 48 of the handle forced over the particular parts 62 or 63 30 of the strut 53 and brought back again into groove 61. The refrigerator is then closed and may be carried about as desired. Due to the height of the strut the handle proper is well above the cover C, and is hence conveniently accessible.

35 Our invention is highly advantageous in that an extremely simple and practical device is provided whereby articles may be cooled and conveniently carried about. By constructing the refrigerator with a skeleton frame considerable 40 saving in weight is procured, so that the refrigerator is extremely light and can be easily handled. With our invention the insulating material gives a panel effect to the refrigerator and when properly painted or enameled gives the 45 refrigerator an extremely pleasing and attractive appearance. By means of the heat transmission seal employed, transmission of heat from the exterior to the interior of the refrigerator through conduction by metal is almost entirely prevented. 50 The latching device is extremely simple to operate and the cover can be quickly taken off and re-applied as desired. When the cover is removed the entire upper end of the container within the refrigerator is open and accessible permitting 55 the articles to be cooled to be easily and quickly removed from or placed in the refrigerator. With our invention an extremely sturdy and rigid construction is formed. By means of the particular construction employed, no fastening means are 60 required for holding the sheets of insulating material in position which are merely held in place through the close fitting of the inner container within the refrigerator in the interior thereof. The handle extending completely across the 65 cover, affords a convenient device by means of which the refrigerator may be carried by either one or two persons.

Changes in the specific form of our invention, as herein disclosed, may be made within the 70 scope of what is claimed without departing from the spirit of our invention.

Having described our invention, what we claim

as new and desire to protect by Letters Patent is:

1. In a refrigerator, a box-like structure having walls and a bottom and open at the top, flanges formed along the upper ends of the walls 5 and extending inwardly into the refrigerator, sheets of insulating material disposed upon the interior of the box-like structure and against the walls thereof, the upper edges of said sheets extending up to said flanges and being held from 10 endwise movement thereby, a container having walls and a bottom, and open at the top, said container fitting within said sheets and holding the same in position within said box-like structure and against said flanges, and flanges formed 15 on the upper edges of the walls of said container and extending outwardly and engaging the upper ends of said insulating sheets, said second named flanges falling short of the first named flanges to form a heat transmission seal 20 between the interior and exterior of the refrigerator.

2. In a refrigerator, an outer box-like structure having walls and a bottom and open at the top, a container within said box-like structure 25 having walls, a bottom and open at the top, insulating sheets disposed between said walls and facing flanges formed on the upper ends of the walls of both the box-like structure and container and engaging the upper edges of the 30 insulating sheets, said flanges being spaced from one another throughout their extent.

3. In a refrigerator, an outer box like structure comprising a bottom, flanges extending upwardly from said bottom, angle corner members attached 35 to said flanges and projecting upwardly therefrom, a band connected to said corner members at their upper ends, insulating sheets disposed in back of said flanges, corner members and band and exposed therebetween, and a container with- 4 in said insulating sheets and free from said box like structure for holding said insulating sheets against said flanges, corner members and band.

4. In a refrigerator, an outer box-like structure open at the top and providing an upper marginal 4 portion, a container within said box-like structure spaced therefrom throughout its entire extent and providing an upper marginal portion spaced from the upper marginal portion of said box-like structure, a cover for said refrigerator, said cover 5 comprising a top extending across the open end of the refrigerator and across the marginal portions of the box-like structure, a sheet of insulating material secured to said top inwardly of the edges thereof to leave a free marginal portion, 5 said sheet of insulating material extending into said container, a liner covering said sheet of insulating material, and flanges formed on said liner and lying adjacent the edges of said sheet of insulating material, said flanges falling short 6 of said top to form a heat insulating seal between the liner and top at the marginal portion thereof, said liner engaging said container to form a relatively tight joint therebetween and said free 6 marginal portion of the top overlying the upper 6 marginal portion of the box-like structure, and an insulating member disposed between the marginal portion of said top and the marginal portion of said box-like structure.
